UNITED STATES PATENT OFFICE

2,613,844

SLIDING DOOR ASSEMBLY

Alfred R. Mounce, Fort Wayne, Ind., assignor to
General Electric Company, a corporation of
New York

Application December 18, 1948, Serial No. 66,032

1 Claim. (Cl. 220—41)

1

My invention relates to doors of the sliding type and particularly to such doors mounted for movement in a horizontal plane.

Sliding doors are frequently employed on display cabinets and similar devices to provide ready access to the interior. When such doors are mounted for movement in a horizontal plane suitable guides are provided to support the door and afford sliding movement. The doors may be provided with rollers to facilitate their movement. When such doors have a greater dimension along their axis normal to their direction of movement there may be a tendency to jam caused by twisting of the door about a generally vertical axis. This twisting may occur in doors provided with rollers as well as in those provided with simple sliding guides. Accordingly it is an object of my invention to provide a sliding door assembly for open top cabinets and the like and including an improved arrangement for preventing jamming of the door during its operation.

It is another object of my invention to provide a sliding door for open top cabinets and the like which is mounted to slide in the direction of its smaller dimension and including an improved arrangement for facilitating the sliding movement and preventing jamming.

Further objects and advantages of my invention will become apparent as the following description proceeds, and the features of novelty which characterize my invention will be pointed out with particularity in the claim annexed to and forming a part of this specification.

For a better understanding of my invention, reference may be had to the accompanying drawing in which Fig. 1 is a perspective view of a portion of a refrigerated display cabinet provided with a door embodying my invention; Fig. 2 is an enlarged plan view of the cabinet shown in Fig. 1; Fig. 3 is a sectional end elevation of the door assembly shown in Fig. 2; and Fig. 4 is an enlarged sectional view on the line 4—4 of Fig. 2.

The cabinet illustrated in Fig. 1 comprises a generally rectangular metal case 10 having a sloping glass display window 11 in the front portion thereof and a sliding glass panel door 12 mounted in the top of the cabinet. The door 12 may be slid toward the rear of the cabinet by pushing a handle 13 toward the rear of the cabinet so that the door slides under a rear portion 14 of the top of the cabinet. The door 12 is of rectangular form and of greater width than depth. When a door of this type is moved it may have a tendency to rotate about a vertical

2

axis and such rotation tends to cause jamming in the guides at the ends of the door. In order to prevent jamming in this manner I have provided a mounting assembly which is more clearly illustrated in Figs. 2, 3 and 4.

As shown in Figs. 2 and 3 the door 12 comprises a rectangular frame 15 provided with four guide engaging elements which have been illustrated as rollers 16 near the four corners of the door; these rollers are arranged to roll on parallel guides 17, one on each side of the door. The top of the cabinet is provided with an opening defined by a suitable frame 18 above the door 12 and forward of the portion 14, and the guides 17 support the door 12 immediately below the opening so that it closes the opening but is arranged to slide under the portion 14 as indicated by the dotted lines in Fig. 3. In order to seal the refrigerated space a suitable gasket 19 is provided along the front edge of the opening, and the rear edge of the opening is sealed by a gasket 20 mounted along the rear edge of the door and extending upwardly to the lower side of the portion 14 of the cabinet. The sides of the door are sealed by strip gaskets 21, the cross sectional form of which is clearly shown in Fig. 4, these gaskets being secured to the side walls of the opening by screws 22 passing through the frame 18 and clamping the frame and the guides 17 securely to a flange 23 formed on the wall of the cabinet 10.

As clearly shown in Fig. 4, the guides 17 are of curved cross section, the rollers 16 normally resting on the lower portion of the curve. It will thus be clear that the two guides provide curves both sloping downwardly toward and under the rollers 16. Thus any lateral movement of the rollers requires that a set of rollers on one side climb up a curved surface. The door is thus biased by gravity to its horizontal position. Furthermore, twisting movement of the door about a vertical axis requires that two of the rollers or elements at opposite sides ride up on the curved surfaces. Thus the gravitational forces tend to prevent the upward movement and consequently tend to prevent the rotation of the door about a vertical axis. Because rotation of the door is resisted by the action of the rollers and the guides, any tendency of the door to jam by twisting is effectively prevented. In this connection it should be noted that because of the increased upward steepness of the slope of the guides, the resistance to twisting increases as the degree of twisting increases. Thus, there is no abrupt stopping of the twisting movement with possible jamming as would be the

case with a positive stop. Obviously, the operation of the supporting arrangement to prevent this twisting and jamming is applicable whether the supporting elements are in the form of rollers 16 or are some other form of supports, such as frictional slide elements. The construction of the curved guides also facilitates the use of sufficient space between the door and the guides along the edges so that the gaskets 21 may be of readily flexible material and can maintain a seal without interfering with the operation of the door.

Doors constructed in accordance with my invention are particularly suitable for applications wherein elongated narrow openings are desirable and in which it is desired, furthermore, to provide an uninterrupted glass area. The arrangement whereby the door may be moved in the direction of its shorter axis without jamming makes it possible to provide a single large door with an uninterrupted glass area rather than providing several smaller sections each of which would slide with little tendency toward jamming.

While I have illustrated and described a particular form of my invention as applied to a refrigerated display case, other applications will readily be apparent to those skilled in the art. I do not, therefore, desire my invention to be limited to the specific embodiments shown and I intend in the appended claim to cover all modifications within the spirit and scope of my invention.

What I claim as new and desire to secure by Letters Patent of the United States is:

A sliding door assembly for open top cabinets and the like comprising an elongated rectangular door, a pair of oppositely facing parallel guides

for supporting said door in a substantially horizontal plane with the shorter sides of said door adjacent and parallel to said guides, pairs of supporting elements mounted on said door near the corners thereof for engagement with respective ones of said guides to support said door in spaced relation to said guides, said guides having cross sections sloping outwardly and upwardly with increased steepness and said elements being arranged normally to move along the lower relatively flat portions of said guides whereby forces tending to twist said door about a vertical axis are opposed by the movement of two diagonally located ones of said elements upwardly against the increasing slope of said guides and jamming of said door is prevented, and strip gaskets of readily flexible material secured along said guides and contacting said door for closing the spaces between said door and said guides and for affording easy movement of said door along said guides and laterally thereof while maintaining sealing engagement between the guides and the door.

ALFRED R. MOUNCE.
